UNITED STATES PATENT OFFICE.

AXEL JOHNSON, OF OAKLAND, CALIFORNIA, ASSIGNOR TO AMERICAN CAN COMPANY, OF SAN FRANCISCO, CALIFORNIA, A CORPORATION OF NEW JERSEY.

APPARATUS FOR RE-FORMING THE FLANGES OF CAN-BODIES.

1,196,695.

Specification of Letters Patent. Patented Aug. 29, 1916.

Application filed January 4, 1916. Serial No. 70,225.

To all whom it may concern:

Be it known that I, AXEL JOHNSON, a citizen of the United States, residing at Oakland, in the county of Alameda and State of California, have invented certain new and useful Improvements in Apparatus for Re-forming the Flanges of Can-Bodies, of which the following is a specification.

The present invention relates to a continuously operating machine for reforming the flanges on the bodies of cans used for the preservation of food products or other materials, after said flanges have become distorted.

In the use of the so-called sanitary cans, the open end of the can body is usually flanged before the can is filled, and sometimes before the can is shipped from the manufacturer to the canner. It frequently happens, therefore, that the flange is damaged and becomes distorted before the can is ready for the sealing operation, and since a distorted flange is exceedingly apt to cause a leaky seam, it is of importance to reform all such distorted flanges.

The object of the present invention is to provide a machine for the described purpose, which operates on either a filled or an empty can, and which, by the continuous and uninterrupted motion of its parts, performs the desired function with the greatest possible efficiency and economy.

In order to comprehend the invention, reference should be had to the accompanying sheets of drawings, in which—

Figure 1 is a perspective view of the complete machine. Fig. 2 is a part sectional elevation taken on a plane passing through the vertical axis of the machine. Fig. 3 is a part sectional plan taken, in the direction of the arrows, on the line $x-x$ of Fig. 2. Fig. 4 is a vertical sectional detail taken, in the direction of the arrows, on the irregular line $y-y$ of Fig. 2. Fig. 5 is a part sectional detail of one of the flange reforming units of the machine.

In the drawings and referring particularly to Figs. 1 and 2 thereof, the numeral 1 represents a central vertical shaft, rotatably mounted in an upwardly extending hub 2 carried by a suitably formed base or supporting member 3. A circular horizontal plate 4, having its rim 4' up-turned to form a pan to catch any material that may be spilled from the cans in their travel through

the machine, surrounds said hub 2. A chamber 5 is formed in the upper part of the base 3, within which are a pair of inter-meshing bevel gears 6 and 7, fixed respectively upon the lower end of the vertical shaft 1 and the inner end of a horizontal drive shaft 8 projecting through the base 3 and carrying upon its outer end a belt pulley 9, or other means not illustrated, for receiving power from an outside source.

Journaled upon the shaft 1 above the hub 2, and spaced therefrom by a sleeve 10, is a stationary cylindrical cam member 11, Figs. 1 and 2 of the drawings. Dowels 12 retain said spacing ring 10 and said cam member 11 stationary with respect to the hub 2.

Carried by the upper end of the shaft 1 is a horizontally rotatable turret 13, in the peripheral region of which are fixed a plurality of depending spindles 14, each provided at its lower end with a flange reforming die 15. In the particular form of machine illustrated in the accompanying drawings, four of these spindles and dies are shown, but it is understood that any number, within the limits of structural practicability, may be used. In like manner, the flange reforming dies may be round, as herein illustrated, or any other shape, depending on the shape of can whose flange is to be reformed.

Mounted for vertical movement upon each spindle 14 is a sleeve 16. A key 17 therein, coacting with a key-way 18 in said spindle 14, prevents said sleeve from rotating about said spindle, without interfering with its vertical sliding movement thereon. The sleeve 16 carries, upon an inwardly projecting stud 19, a cam-following roller 20, adapted to lie within and follow a cam-groove 21 formed in the exterior of the member 11, and upon its lower end an enlarged semi-cylindrical clamping portion 22, within which is carried a semi-circular die ring 23, Figs. 2 and 5 of the drawings. A complementary semi-cylindrical clamping member 24 and semi-circular die ring 25 are pivotally connected, by means of arms 26 and a pin 27, with the sleeve 16, so as to swing in a vertical plane toward and away from the fixed clamping member 22, as shown in Figs. 1, 2 and 5 of the drawings.

A yoke 28 is pivotally mounted upon the sleeve 16 by means of a pin 29 parallel to the pivot pin 27 and on the opposite side of

- 2
- said sleeve therefrom. This yoke 28 carries on its inner end a follower 30, adapted to lie within and follow a cam groove 31 formed in the peripheral surface of the member 11 below the groove 21. One of the arms of said yoke is extended outwardly beyond the pivot 29, and carries upon said extension a segmental gear 32, adapted to mesh with a pinion 33 fixed to one of the arms 26 of the movable clamping jaw 24. Thus the vertical movement of the cam follower 30 is transferred to said clamping jaw 24 to cause the same to swing toward or away from the stationary jaw 22.
- 15 The horizontal drive shaft 8 has fixed upon it a bevel pinion 34, Figs. 2 and 3 of the drawings, which meshes with two oppositely disposed bevel gears 35 and 36, mounted respectively upon the inner ends of two 20 suitably journaled alined shafts 37 and 38. Said shafts carry at their outer ends the respective belt pulleys 39 and 40, over which run, and by which are driven, in opposite directions, the conveyer belts 41 and 42.
- 25 Figs. 1, 2 and 3 of the drawings, adapted respectively to deliver cans 43 to and discharge the same from the operating mechanism of the machine. Suitable guide rails 44, supported by means of brackets 45, are 30 provided to guide said cans 43 in their proper paths while being carried by the conveyer belts 41 and 42.
- 35 Mounted in the supporting frame parallel to and beneath the drive shaft 8 is a rock shaft 46, Figs. 2, 3 and 4 of the drawings, which carries at one end a lever 47 having a roller 48 adapted to engage and follow an eccentric cam 49 upon said drive shaft 8. An upwardly extending arm 50, 40 Figs. 1, 2 and 3 of the drawings, is fixed upon the other end of said rock shaft 46, and is provided with a forked end 51 which embraces a transverse rod 52, slidably mounted in brackets 53. A spring 54, Figs. 1 and 45 2 of the drawings, operating between one of said brackets 53 and a collar 55 on the rod 52, normally holds said rod in the position shown in Fig. 1, so that its end portion 56 extends across the path of travel of 50 the incoming cans 43, and arrests the progress thereof. The rod 52 is withdrawn out of the path of travel of said cans, by means of the cam 49 and the intervening mechanism, at the proper time to insure that the 55 can, thus permitted to advance from the position A, Figs. 1 and 3 of the drawings, will be carried into exact registry with one of the clamping members carried by the continuously revolving turret 13.
- 60 The can 43 having been carried to the position B, the roller 30, following the cam groove 31, actuates the described mechanism to close the movable clamping jaw 24, Fig. 1 of the drawings, upon said can 43 to clamp 65 the same firmly between said movable jaw 24 and the relatively fixed jaw 22. Immediately thereafter the roller 20, following the cam groove 21, causes the sleeve 16 and the clamping jaws 22 and 24 to be raised vertically, and by so doing to lift the can 70 43 secured therewithin clear of the conveyer belt 41, as shown in Fig. 5 of the drawings. This lifting continues until the position C, Figs. 1, 2 and 3, is reached, at which point the flange 43' of the can 43 is pressed between the lower die ring composed of the complementary semi-circular members 23 and 25, and the relatively fixed die 15, whereby any irregularities in said flange 43' 75 are stamped out, and the same is restored to perfect form. The can 43 is then lowered, by means of the roller 20 and the cam groove 21, until the position D, Fig. 3 of the drawings, is reached, at which point said can rests upon the discharge conveyer 42, 80 whereupon the roller 30 operates to open the clamping jaws 24 and thus release the can, which is carried away from the machine by said conveyer 42.
- 85 The invention has been described and 90 illustrated herein in its preferred form. However, changes may be made in the form and construction of the device without in any way affecting the principles of the invention, and I therefore do not wish to be 95 limited in this regard, but on the contrary, I wish to be understood as claiming the invention as broadly as the state of the art will permit.
- Having thus described my invention, what 100 I claim as new and desire to protect by Letters Patent is:—
1. In an apparatus for the described purpose, a relatively stationary die member, and movable means for engaging and lifting a 105 flanged can body to press said flange between said engaging means and said die.
  2. In an apparatus for the described purpose, a relatively stationary die member, movable clamping devices for receiving and 110 embracing the flanged end of a can body, and means for moving said clamping devices to press the flange of said can body between said clamping devices and said die.
  3. In an apparatus for the described purpose, a relatively stationary die member, 115 movable clamping devices adapted to embrace a flanged can body, a die ring within said clamping devices, and means for moving said clamping devices to press said 120 flange between said die and said die ring.
  4. In an apparatus for the described purpose, the combination with conveyer means for supplying and discharging cans, of a die member, and means for engaging a 125 flanged can body, removing the same from said conveyer, lifting the same to bring the flange thereof into engagement with said die, and then depositing the same upon said conveyer to be discharged from the machine. 130

5. In an apparatus for the described purpose, the combination with conveyer means for supplying and discharging cans, of a die member, movable clamping devices for embracing a flanged can body, and means for moving said clamping devices to remove said can body from said conveyer, to bring the flange thereof into engagement with said die, and then to deposit said can body upon said conveyer to be discharged from the machine.

6. In an apparatus for the described purpose, the combination with conveyer means for supplying and discharging cans, of a die member, movable clamping devices for embracing a flanged can body, a die ring within said clamping devices, and means for moving said clamping devices to remove said can body from said conveyer, to press the flange thereof between said die and said die ring, and then to deposit said can body upon said conveyer to be discharged from the machine.

7. In an apparatus for the described purpose, a relatively stationary die member, movable devices for receiving and clamping a flanged can body in axial alinement with said die, and means for moving said clamping devices to press the flange of said can body between said clamping means and said die.

8. In an apparatus for the described purpose, a relatively stationary die member, means for receiving a filled open ended flanged can and conveying the same into axial alinement with said die, clamping devices for embracing the flanged end of said can, and means for raising said clamping devices to press the flange of said can between said clamping devices and said die.

9. In an apparatus for the described purpose, a relatively stationary die member, means for receiving a filled open ended flanged can and conveying the same into axial alinement with said die, clamping devices for embracing the flanged end of said can, means for raising said clamping devices to press the flange of said can between said clamping devices and said die, and means for removing said can from said clamping devices after said flange has been pressed.

10. In an apparatus for the described purpose, a rotating turret carrying a die, means for receiving a flanged can body and positioning the same in axial alinement with said die, clamping devices associated with said turret for embracing said can body and lifting the same to press the flange thereof between said clamping devices and said die.

11. In an apparatus for the described purpose, a rotating turret carrying a die, means for receiving a flanged can body and positioning the same in axial alinement with said die, clamping devices associated with

said turret for embracing said can body, means for lifting said clamping devices to press the flange of said can body between said clamping devices and said die, and means for removing said can body from said clamping devices.

12. In an apparatus for the described purpose, a rotating turret carrying a die, means for positioning a flanged can body in axial alinement therewith, clamping devices associated with said die and actuated by the rotation of said turret to embrace said can body and lift the same to press the flange thereof between said clamping devices and said die.

13. In an apparatus for the described purpose, a rotating turret carrying a die, means for positioning a flanged can body in axial alinement therewith, clamping devices associated with said die and actuated by the rotation of said turret to embrace said can body, means actuated by the rotation of said turret to raise said clamping devices to press the flange of said can body between said clamping devices and said die, and means for removing said can body from said clamping devices.

14. In an apparatus for the described purpose, a rotating turret carrying a fixed spindle with a flange reforming die mounted upon the end thereof, a sleeve slidably mounted upon said spindle, clamping devices carried by said sleeve, means for positioning a flanged can body within the sphere of said clamping devices, means actuated by the rotation of the turret to close said clamping devices about said can body, means actuated by the rotation of the turret to lift said sleeve to press the flange of said can body between said clamping devices and said die, and means for removing said can body from the sphere of said clamping devices.

15. In an apparatus for the described purpose, a rotating turret carrying a plurality of depending spindles each having a flange reforming die carried upon the end thereof and a sleeve slidably mounted thereon, means for successively positioning flanged can bodies in axial alinement with said dies, clamping devices carried by said sleeves and actuated by the rotation of said turret to embrace said can bodies, and means actuated by the rotation of said turret to successively lift said sleeves to press the flanges of said can bodies between said clamping devices and said dies.

16. In an apparatus for the described purpose, a rotating turret carrying a plurality of depending spindles each having a flange reforming die carried upon the end thereof and a sleeve slidably mounted thereon, means for successively positioning flanged can bodies in axial alinement with said dies, clamping devices carried by said sleeves and actuated by the rotation of said turret to successively lift said sleeves to press the flanges of said can bodies between said clamping devices and said dies.

ated by the rotation of said turret to embrace said can bodies, a die ring within each of said clamping devices, means actuated by the rotation of said turret to successively lift said sleeves to press the flanges of said can bodies between said die rings and said dies, and means for removing said can bodies when released by said clamping devices.

In testimony whereof I have signed my name to this specification in the presence of 10 two subscribing witnesses.

AXEL JOHNSON.
